Primary Examiner — Barbara Fox*Assistant Examiner* — Dana K Weiland(74) *Attorney, Agent, or Firm* — Schwegman Lundberg & Woessner, P.A.(57) **CLAIM**

The ornamental design for a portable computing device, as shown and described.

DESCRIPTION

FIG. 1 is a front view of a portable computing device, showing our new design.

FIG. 2 is a rear view thereof.

FIG. 3 is a left side view thereof.

FIG. 4 is a right side view thereof.

FIG. 5 is a top view thereof.

FIG. 6 is a bottom view thereof.

FIG. 7 is a top-left-front perspective view thereof.

FIG. 8 is a top-left-rear perspective view thereof.

FIG. 9 is a bottom-right-rear perspective view thereof; and,

FIG. 10 is a bottom-right-front perspective view thereof.

The broken lines shown in the drawings depict portions of the portable computing device that form no part of the claimed design.

1 Claim, 8 Drawing Sheets(56)
